UNITED STATES PATENT OFFICE.

JOHN K. ROGERS, OF BROOKLINE, MASSACHUSETTS.

DESIGN FOR A FONT OF PRINTING-TYPES.

SPECIFICATION forming part of Design No. 11,978, dated October 12, 1880.

Application filed March 16, 1880. Term of patent 3½ years.

To all whom it may concern:

Be it known that I, JOHN K. ROGERS, of the town of Brookline, in the State of Massachusetts, have invented and produced a new

and original Design for a Font of Printing-
Types, of which the following is a specifica-
tion, the nature of the design being clearly
shown in the accompanying typographical im-
pressions, to which reference is made.

My design consists of a font of capital let-
ters, with figures, points, short-and, and dol-
lar-mark, shaded with a single line on the bot-

tom and right hand, the swell in the round
letters terminating in an obtuse point, and the
A, D, H, M, N, O, Q, U, V, W, and Y having 15
a diagonal line across the open spaces.

What I claim as new is—

The font of printing-types, as described and
shown.

JOHN K. ROGERS.

Witnesses:

F. S. FLOCKEN,
D. WEBSTER ROGERS.
